ATTORNEYS

The housing is formed to receive the inner filtering unit 18 which, as illustrated in Figs. 2 and 3 is formed with a base 33, side walls 34 and 35 and an upper panel 36 and a tapering core extends longitudinally through the center. As illustrated in Fig. 6 the core is formed with a base 37, side walls 38 and 39 and an upper panel 40 at one end and a similar unit including a base 41, side walls 42 and an upper panel 43 is provided in the opposite end. The two units, which form the passages 21 and 22 are separated by the partition 23 and the partition is provided with a V-shaped ridge 44, as shown in Fig. 8. The side and end walls of the core and also the base portions and upper panels converge from the end plates 13 and 14 of the housing to a point 45, at the center and, at this point, the partition 23 forms a complete closure.

A peripheral area 46 between the outer walls 33, 34, 35, and 36 and the inner frustro-conical shaped unit providing a core is filled with crinkly copper or other suitable filtering material whereby all foreign matter and particularly volatilized oils suspended in the exhaust gases are arrested or removed from the exhaust gases passing through the housing.

The inner converging walls of the unit 18 are suspended from the outer walls by bars 47, 48, and 49 secured in position by welding, brazing, or other suitable means, as shown in Fig. 3, and similar bars are provided at the opposite end. The inner walls, such as the walls 37, 38, 39 and 40 at one end and 41, 42, and 43 at the opposite end are perforated or formed with wire mesh or other suitable material.

The cover, including the outer panel 15, inner panel 16 and layer of asbestos material 17 is secured to the housing by hinges 50 at one side and by clasps including loops 51 that engage keepers 52 that are secured to the flanges 32 of the cover and are actuated by the pivotal lever 53 by which the loops 51 are drawn downwardly, similar to latches of a trunk.

In use, the smog control box, as indicated by the numeral 54 is connected in the tail pipe or exhaust 55 of a vehicle having a chassis 56 and with all exhaust gases of the vehicle passing through the housing the smog forming elements suspended in the gases are removed.

With the inner filtering unit 18, formed as illustrated and described, the unit may be removed for cleaning and readily replaced.

With the unit installed, as illustrated in Fig. 1, the exhaust gases pass through the inlet 19 into the area 21 in one end of the housing, through perforations in the walls 37, 38, 39 and 40 into the filtering chamber 46 and from the filtering chamber through the walls 41, 42, and 43 into the chamber 22 from which they exhaust through the connection 20.

It will be understood that modifications, within the scope of the appended claims, may be made in the design and arrangement of the parts without departing from the spirit of the invention.

What is claimed is:

1. In a smog control device, the combination which

comprises an elongated rectangular-shaped housing having a base with side and end walls extended upwardly therefrom and having a liquid reservoir extended downwardly from the base, an inlet connection on the end wall at one end of the housing, an outlet connection on the end wall at the opposite end of the housing, and a filter unit having a base, side walls, and an upper panel and having a core with perforated diverging inner walls extended from a transversely disposed partition at the center of said core to said end walls, said core being positioned centrally of said housing and said diverging inner walls being spaced from the base, side walls and upper panel of said filter unit, and crinkly copper in the space between the base, upper panel and side walls and the diverging walls of said core and the said parts being assembled whereby exhaust gases of an engine pass into one end of the device, through the crinkly copper positioned in the space between the walls of the filter unit and core and exhaust through said outlet connection.

2. In a smog control box, the combination which comprises an elongated housing rectangular-shaped in elevation and rectangular-shaped in section and having a base with side and end walls extended upwardly therefrom, said base having a depressed portion therein and said depressed portion being formed to contain a liquid, and a filter unit having a base, side walls, and an upper panel positioned in the housing and having a core with included lower, upper and side walls extended from a transverse partition positioned at the center of the core to the end walls of the housing and with the lower walls of the core diverging from the transverse partition to the end walls of the housing, said lower walls being spaced from the upper and side walls of said filter unit, and a cover hinged, at one side to a side wall of the housing and having latch elements for clamping the cover upon the upper end of the housing, the space between the upper, and side walls of the filter unit and the lower inclined walls of the core containing crinkly copper.
